DESIGN FOR A COMBINED HEEL AND COUNTER UNIT FOR A SHOE OR SIMILAR ARTICLE

Edna S. Payne, New York, N. Y.

Application April 18, 1946, Serial No. 128,737

Term of patent 7 years

(Cl. D7—5)

To all whom it may concern:

Be it known that I, Edna S. Payne, a citizen of the United States and a resident of New York, in the county of New York, State of New York, have invented a new, original, and ornamental Design for a Combined Heel and Counter Unit for a Shoe or Similar Article, of which the following is a specification, reference being had to the accompanying drawing, forming a part thereof.

In the drawing:

Figure 1 is a front perspective view of a combined heel and counter unit for a shoe or similar article showing my new design.

Figure 2 is a side view thereof; and,

Figure 3 is a rear view thereof.

I claim:

The ornamental design for a combined heel and counter unit for a shoe or similar article, substantially as shown.

EDNA S. PAYNE.
